Attorney

UNITED STATES PATENT OFFICE.

AUGUST BURKHARDT, OF CHAMPAIGN, ILLINOIS.

DESIGN FOR A DOMINO GAME PIECE OR BLOCK.

49,174.

Specification for Design.

Patented June 13, 1916.

Application filed April 15, 1916. Serial No. 91,490. Term of patent 3½ years.

To all whom it may concern:

Be it known that I, AUGUST BURKHARDT, a citizen of the United States, residing at Champaign, in the county of Champaign and State of Illinois, have invented a new, original, and ornamental Design for Domino Game Pieces or Blocks, of which the following is a specification, reference being had to the accompanying drawing, forming a part thereof.

Figures 1 and 2 represent a perspective and a longitudinal sectional view, respectively, of a domino game piece or block, showing my new design.

I claim:

The ornamental design for a domino game piece or block as shown.

AUGUST BURKHARDT.

Witnesses:

BEN M. PRICE,

FRED M. PRICE.
